US0D1030701S

(12) **United States Design Patent** (10) Patent No.: **US D1,030,701 S**
(45) Date of Patent: ** Jun. 11, 2024

(54) **HEADPHONE**

(71) Applicant: **Dongguan Liesheng Electronic Technology Co., Ltd.**, Dongguan (CN)

(72) Inventors: **Xi Wu**, Dongguan (CN); **Yujiao Yang**, Dongguan (CN); **Hong Zeng**, Dongguan (CN); **Hao Chen**, Dongguan (CN); **Hao Ma**, Dongguan (CN)

(73) Assignee: **Dongguan Liesheng Electronic Co., Ltd.**, Dongguan (CN)

(**) Term: **15 Years**

(21) Appl. No.: **35/517,797**

(22) Filed: **Jun. 26, 2023**

(80) **Hague Agreement Data**

Int. Filing Date: **Jun. 26, 2023**

Int. Reg. No.: **DM/230053**

Int. Reg. Date: **Jun. 26, 2023**

Int. Reg. Pub. Date: **Jul. 14, 2023**

(30) **Foreign Application Priority Data**

May 17, 2023 (CN) 202330290305.0

(51) **LOC (14) Cl.** **14-01**

(52) **U.S. Cl.**

USPC **D14/205**

(58) **Field of Classification Search**

USPC D14/205, 188, 192; D24/174; 128/864-866; 381/380-381

CPC H04R 25/00; H04R 25/02; H04R 1/10; H04R 1/1066; H04R 1/1016; H04R 5/033; H04R 5/0335; H04R 1/105; H04R 1/1033; H04R 1/28; H04R 1/02; H04R 9/06; H04R 1/1008; G06F 3/162; F21V 23/0407; F21V 23/0414; F21V 33/0052

Primary Examiner — Paula Allen Greene

(57) **CLAIM**

The ornamental design for a headphone, as shown and described.

DESCRIPTION

1. Headphone

1.1 : Front

1.2 : Back Perspective

1.3 : Left

1.4 : Right

1.5 : Top

1.6 : Bottom

1.7: Front Perspective

1 Claim, 7 Drawing Sheets
